UNITED STATES PATENT OFFICE.

JOHN FRANKLIN LAYCOOK, OF HUNTINGDON, TENNESSEE.

CURRENT-MOTOR.

1,332,299.

Specification of Letters Patent.

Patented Mar. 2, 1920.

Application filed August 8, 1918. Serial No. 248,950.

To all whom it may concern:

Be it known that I, JOHN F. LAYCOOK, a citizen of the United States, and a resident of Huntingdon, in the county of Carroll and State of Tennessee, have invented a new and Improved Current-Motor, of which the following is a full, clear, and exact description.

This invention relates to water motors and particularly to what may be termed a current motor, and has for an object the provision of an improved construction which will utilize either a fast or slow moving body of water to produce power capable of use in commercial pursuits.

Another object of the invention is to provide a current motor forming a single element or structure which may be used alone or in connection with similar elements or structures.

A further object of the invention is to provide a current motor which will utilize either deep or shallow water which is moving through the provision of an improved arrangement of substantially horizontal movable planes and connecting parts for transmitting the motion of the planes into a rotary motion.

In the accompanying drawings:

Figure 1 is a top plan view of a current motor disclosing an embodiment of the invention.

Fig. 2 is a longitudinal vertical section through Fig. 1 on line 2—2.

Fig. 3 is an enlarged horizontal sectional view through the upper part of the mechanism shown in Fig. 1.

Fig. 4 is a fragmentary sectional view through Fig. 3 on line 4—4.

Fig. 5 is a fragmentary view similar to Fig. 4 disclosing how the re-setting knobs operate the clutches embodying certain features of the invention.

Fig. 6 is an edge view of one of the brackets and associate parts shown in Fig. 5.

Fig. 7 is a section through Fig. 8 on line 7—7.

Fig. 8 is a top plan view of the plane and associate parts shown in Fig. 7.

Fig. 9 is a detail fragmentary sectional view through Fig. 14 on line 9—9.

Fig. 10 is a view similar to Fig. 9, but disclosing the parts in the next position ob-

cupied to that shown in Fig. 9, the same being taken on line 10—10 of Fig. 14.

55

Fig. 11 is a view similar to Fig. 10 but showing a still further position of the respective parts, the same being taken on line 11—11 of Fig. 14.

Fig. 12 is a detail fragmentary view 60 showing a pawl and ratchet structure embodying certain features of the invention.

Fig. 13 is a view similar to Fig. 11, but showing the parts in a further different position occupied when the parts are about to 65 release the power plane for another trip.

Fig. 14 is an enlarged sectional view through Fig. 1 on line 14—14.

Fig. 15 is a fragmentary sectional view 70 through Fig. 14 on line 15—15.

Referring to the accompanying drawings by numerals, 1 indicates a specially prepared flume which is substantially U-shaped in cross section, said flume having a pair of grooves 2 and 3 on each side extending for 75 the full length of the flume so as to accommodate the various guiding rollers 4 on the planes 5 and 6 which act as the power members of the motor. These planes move back and forth for half the length of the flume 1 80 and act successively whereby the power shaft 7 is continually rotated, said planes being connected therewith as hereinafter fully described. Plane 5 is provided with a frame 8 to which a cable 9 is secured in any 85 desired manner, said cable passing over a guiding pulley 10 and a guiding pulley 11 and from thence to the drum 12 around which it is passed one or more times as may be desired and then over the guiding pulley 13 to a point 14 where it is fastened again to the frame 8. When the water is pressing against the plane 5 the cable 9 will be pulled so as to travel as indicated by the arrow 15 while the part of the cable connected at 14 will be paid out as indicated by the arrows 16. Only one cable 9 has been described, but as shown in Fig. 1, there are two cables provided, and as these cables and associate parts are identical the description 90

of one will equally apply to the other, there being two that the structure may be more evenly balanced. The plane 6 on the downstream side of the flume 1 is provided with a frame 17 to which the cable 18 is secured, 105 said cable passing over pulleys 19 and 20

and a small guiding pulley 21 to the drum 22 and around the drum one or more times. From drum 22 cable 18 passes downwardly over the guiding pulley 23, from thence back 5 to the frame 17 where it is connected at 24 to said frame. In this way when the cable 9 is operating as shown in Fig. 2, and as just described, cable 18 will be paying out its upper section as indicated by arrow 25 10 and will be drawing in the section indicated by the arrow 26. It will thus be seen that the plane 6 and associate parts are idle when moving back to the position to begin its power stroke while plane 5 is moving on its 15 power stroke. As soon as plane 5 has accomplished its full power stroke as herein-after described, the water will be released and engage plane 6 and move same toward the discharge or downstream end 27 of flume 20 1, and as it is moved the section of cable 18 indicated by arrow 26 will be pulled so as to rotate the drum 22 in the proper direction for giving a continuous rotation to shaft 7 in the same direction that it was rotated by power transmitted from plane 5.

In Figs. 1 and 2 the motor is shown with the planes 5 and 6 and associate parts positioned midway of the stroke of plane 5, while in Fig. 3 an enlarged detail view is 30 disclosed wherein it is illustrated how the parts operate just as and during the period when the plane 5 has completed its stroke and when the plane 6 is about to begin its power stroke. In this view plane 5 is shown 35 as engaging the releasing stops 28 which are slidably mounted on suitable guiding bearings 29, which are connected with the bell crank levers 30 by the usual bolts 31 extending through slots 32 in the respective levers. The respective levers 30 are provided with pivotal pins or bolts 33, which extend through the cross bar 34 of flume 1 as shown in Fig. 4, and are rigidly secured to an arm 35 substantially the same shape and 45 size as the short leg of lever 30, said arm having an aperture therein as shown in Fig. 5, through which the section of cable 9, indicated by the arrow 16 extends, so that the ball or stop 36 rigidly secured thereto at the 50 proper place will engage the arm 35 and move the same for shifting the long leg of lever 30 to the position shown in Fig. 3 when moved therefrom, as hereinafter fully described. However, as the plane 5 moves the 55 stop 28 and lever 30 will be moved to the dotted position shown in Fig. 3 for shifting the clutch 37. The long leg of lever 30 is bifurcated as shown in Figs. 3 and 4 and carries oppositely positioned pins fitted into 60 the groove 38 of the hub structure of clutch 37, which clutch is provided with a number of pins 39 extending through apertures in the clutch plate 40 keyed or otherwise rigidly

secured to the shaft 7. It will thus be seen 65 that when the plane 5 strikes the stops 28 and moves the parts associated therewith drum 12 will be disconnected from the plate 40 and consequently disconnected from shaft 7, so as not to transmit any power thereto or 70 receive any power therefrom directly. In order to cause the drum 12 to rotate in the opposite direction and thereby pay out the cable, said drum is provided with an internal gear 41 which is designed to receive the 75 pinion 42 carried by rod 43 mounted on suitable bearing on one of the cross bars 34. A grooved sleeve 44 is rigidly secured to shaft 43 so as to accommodate the pins 45 of lever 46 as shown more particularly in Fig. 80 4, whereby when the bell crank lever 30 is moved as just described, so that the parts will assume the dotted position shown in Fig. 3, the pinion 42 will be moved into mesh with gear 41. A gear 47 is rigidly secured to shaft 7 and continually meshes with the long pinion 48 whereby the shaft 43 and associate parts may be moved back and forth without pinion 48 being moved out of mesh with gear 47. These gears are properly proportioned to pay out the bottom section of 85 the cable 9 and pull in the top section in proportion to the movement of the plane 6 so that plane 5 will be positively moved to the proper place for beginning its stroke 90 near the up-stream end of flume 1.

Simultaneously with the shifting of the clutch 37 and associate parts by the operation of stops 28 plane 6 on the down stream side of shaft 7 will move the T-shaped lever 100 49, through the action of the bracket 50 rigidly secured to the frame 17. As bracket 50 moves in the direction of arrow 51 the clutch 52 will be moved over so that the pins 53 will extend into the apertures 54 formerly 105 occupied by the pins 39 of drum 12. The clutch 52 and associate parts are identical with the clutch 37, but move in opposition thereto so as to connect the pulley or drum 22 to shaft 7 as soon as clutch 37 releases 110 drum 12. The long leg of lever 49 is provided with a bifurcated bar having pins coacting with lever 55 in the same manner to the way lever 30 is made and coacts with lever 46, so that no additional description 115 will be needed, except that the lever 55 shifts pinion 56 into and out of engagement with an internal rack 57 carried by the drum 22, and at the same time causes the pinion 58 to remain in mesh with gear wheel 59 rigidly 120 secured to shaft 7. By the use of the gear wheels 47 and 59 and associate parts the drums 12 and 22 are positively driven for pulling the respective planes 5 and 6 back to the starting point for each power stroke. 125

Referring again to the action of plane 5 when it is moving on its power stroke and is about to reach the position shown in Fig.

3, the parts are in the position shown in Fig. 9 with the power blade 60 locked in the vertical position by the vertically movable locking plate 61. The power blade 60 is divided into three sections as shown in Fig. 14, namely, a central section 62 and side sections 63. These sections are provided and also other mechanism associated therewith whereby the side sections 63 will be first released when moved to the position shown in Fig. 3 and then shortly thereafter the central section 62 will be released so that the water will more gradually act on plane 6. The releasing action for the central section 62 is the same as the side sections though a brief interval thereafter. As soon as the parts reach the position as shown in Fig. 9 the gear wheel 64 meshes with a short rack 65 and as it passes thereover the parts are moved to the position shown in Fig. 10. As the gear wheel 64 rotates the shaft 66 consequently rotates the respective pinions 67. Each of the side pinions 67 meshes with a coacting pinion 68 which is rigidly secured to the respective shaft 69 to which the drums 70 and 71 are rigidly secured. Drum 70 is of greater diameter than drum 71 as it winds and then pays out a greater length of cable. Connected with the small drum 71 is a cable 72 which passes over an idler 73 and is secured at 74 to an arm 75. This arm is pivotally mounted at 76 on the frame of the plane 5. The end of the arm 75 opposite the connecting point 74 carries idlers 77 and over which the cable 78 extends, said cable being rigidly secured to the large drum 70 and to the end 79 of a pushing lever 80, said pushing lever having a bent over hook end 81 and is pivotally mounted at 82 on arm 75 so that when the drums are rotated by action of rack 65 and the various gears just described, cables 72 and 78 will be slackened, but the lever 80 will not move down to the position shown in Fig. 10 until the long leg of the bell crank lever 83 strikes against the stationary stop 84. When this occurs the rod 85 (Fig. 8) is pulled and consequently the bar 86 is swung on its pivotal point 87 whereby the pin 88 is moved to swing the arc-shaped rack 89 out of engagement with the pawl 90, which pawl is pivotally mounted on arm 75 and which is allowed a limited pivotal movement by the spring 91. As soon as the pawl 90 has been disengaged as just described the weight of the lever 80 and associate parts will cause the various parts to automatically move downwardly under the action of gravity to the position shown in Fig. 10 and at the same time bring the cables 72 and 78 under tension. The parts will remain in this position until the plane 5 has been moved toward the down stream end of the flume 1 a sufficient distance for causing the end of bell crank lever 92 to engage the stop 93 whereupon the rod 94 will be lowered and the locking bar 61 lowered to a position out of the way of the blade 60, whereupon the blade 60 will move upwardly to the position shown in Fig. 11 and will move arm 75 and associate parts also to an upper position. It will be understood that blade 60 is divided into a number of sections as shown in Fig. 14, and that when it is stated that blade 60 will move up to the position shown in Fig. 11 it will be, of course, understood that the blade will move up as heretofore described. The sections 63 will move up first as they are associated with the levers 92 as shown in Fig. 3, while the central section 62 will move up a short time thereafter as the levers 92 associated therewith will engage the stops 93 after levers 92 have engaged the stops 93. This interval of time may be varied as desired by shifting the stops 93. When the parts have assumed the position shown in Fig. 11 the plane 5 has reached the extreme end of its power stroke and has been released for the return movement which is caused by the drums 12 pulling on the sections indicated by arrow 15. When the plane 5 eventually reaches the upstream end of flume 1 the gear wheel 64 engages the rack 65" and moves the parts from the position shown in Fig. 11 to that shown in Fig. 13. It will be, of course, understood that the blade 60 is raised to a horizontal position by the action of the water so that when the rack 65" is engaged for swinging the arm 75 upwardly the hook 81 will freely engage the outer end of the blade 60 and move the same substantially horizontally to the position shown in Fig. 13 where it rests upon the release arm 95. This release arm is held in an elevated position by the cable 96 which passes over suitable pulleys and which is held in proper position by the weight 97 whereby the release arm 95 is normally held in a horizontal position. A reciprocating catch 98 is held by a spring or by any other suitable means over the end of the weight 97 whereby when the weight of the blade 60 is resting on the release arm 95 said weight will not move upwardly and consequently said arm will not move downwardly. A pivotally mounted lever 99 loosely engages the catch 98 and is positioned in the path of movement of blade 60 so that when said blade has been moved for its full distance by the lever 80 it will strike against the lever 99 and thereby cause the catch 98 to release weight 97. This will allow the blade 60 to move downwardly under the action of gravity and engage the water in such a manner that the water will swing the blade to a vertical position, the bar 61 stopping the swinging movement when the blade 60

has reached its vertical position. This completes the return stroke and places the parts in position for a second power stroke. Simultaneously with the movement of lever 80, and the release of the catch 98, the stop or ball 36 (Fig. 5) will engage the arm 35 and shift the same whereby the bell crank lever 30 will be shifted back from the dotted position shown in Fig. 3 to the full line position shown in said figure, whereupon the second power stroke of the plane 5 will act to rotate the shaft 7 in the same direction as before. Simultaneously with the action of the ball 36, as just described, the ball 15 or stop 100 (Fig. 5) will engage the short arm 101 of the lever 49 and shift clutch 52 so as to disengage the clutch disk 40 substantially simultaneously with the engagement of said disk by clutch 37.

20 The down stream side of the motor is the same as the upstream side with a few slight modifications, so that no additional description will be given therefor and the same numerals will be used except for the slight difference in construction. As shown in Fig. 4 the supporting release arm 95' is provided near the center of the flume for the power blades of the lower plane 6, said structure being identical with the member 95 and associate parts shown in Fig. 13. The lower blade 60' is preferably made in one piece, so that the arm 75 and associate parts are arranged one at each end of the blade instead of at three different points as shown 35 in Fig. 14 for the plane 5. When the plane 6 reaches the down stream end 27 of the flume 1 rack 65' and the stop 84' will act in a similar manner to the rack 65 and stop 84 as shown in Fig. 9 for releasing blade 40 60' so that the plane 6 may return and be operated as shown in Fig. 4 so as to go through another power stroke.

It will be seen that each plane has two drums and two cables, there being one cable 45 for each drum. These drums are intermittently connected with the shaft 7 so that said shaft continually rotates in a given direction. The sections 63 are released as shown in Fig. 3 when reaching the end of 50 the power stroke, but by reason of the shaft 66 extending entirely across the plane 5 as shown in Fig. 14 the various arms 75 are operated simultaneously for causing a simultaneous return of the various sections, 55 whereby the blade 60, as shown in Fig. 13, will engage the water and begin its power stroke. In addition to the rack 65' at the upstream end of the flume 1 stops 93" are provided for again moving the bar 61 and 60 associate parts to an upper or locked position. It will thus be seen that when the water is turned on to the flume by any desired means, as for instance by the opening of suitable gates the motor will begin

to run and will continue to run automatically as long as the proper amount of water is allowed to flow through the flume. The moving of the planes in a horizontal direction and the back and forth action thereof permits the use of a comparatively small amount of water with a maximum power. It also permits the use of a comparatively small continuous supply, as no water is necessary except a sufficient quantity for filling the flume in front of the various blades.

What I claim is:

1. A current motor comprising a flume, a pair of planes movable longitudinally of the flume, each of said planes moving substantially one-half the distance of the flume with one plane returning from a power stroke during the time the other plane is on the power stroke, a pair of drums for each of said planes, a shaft extending through said drums, and a plurality of cables from each plane to the drums, a clutch mechanism for connecting and disconnecting the drums with said shaft, and means operated by the respective planes for shifting said clutch mechanism upon the completion of the power stroke of each of said planes.

2. A current motor comprising a flume, a pair of planes movable lengthwise of the flume, a power shaft, a plurality of drums for each of said planes, cables extending from said drums to the respective planes, whereby when the respective planes are on the power stroke said drums will be rotated, a clutch for each of said drums for connecting the drums with said shaft, means actuated by said planes when one of the planes has completed its power stroke for shifting said clutches, and means for releasing the blades of said planes upon the completion of their strokes whereby the water will raise the blades to a horizontal position and hold the same in that position during the return stroke of the respective planes.

3. A current motor comprising a substantially rectangular flume open at both ends and the top, said flume having guiding grooves in each side wall, a pair of oppositely movable planes mounted in said flume, guiding members extending from each of said planes into the respective grooves so as to guide the planes in their reciprocatory movement, a power shaft arranged substantially centrally of the flume, a pair of cables connected at the opposite ends to said planes, a pair of drums for each of said planes around which said cables are looped so that each plane will rotate a certain set of drums, a clutch mechanism for each drum for connecting and disconnecting the same with said power shaft, and means for operating said clutches, said means being operable when either of the planes reach the end of its power stroke.

4. A current motor of the character described comprising a substantially rectangular flume open at both ends and the top, each side of said flume having a pair of 5 spaced grooves, a pair of planes arranged in said flume, guiding means connected to each of said planes extending into said grooves whereby the planes are guided in their reciprocatory movement and are prevented from 10 rotary movement, a power shaft, and means connecting the power shaft with said planes for transmitting power from the planes to the power shaft as the planes operate.

5. A current motor comprising a flume, a 15 pair of planes arranged in said flume adapted to move longitudinally of the flume, a power shaft arranged substantially centrally of the flume, a pair of drums on said power shaft for each plane, a pair of cables 20 for each plane having part thereof looped around the respective drums, a clutch disk rigidly secured to said shaft between each pair of drums, a clutch member carried by each of the drums, means for shifting said 25 clutches into and out of engagement with said clutch disk, means for driving in a reverse direction said drums when disconnected from said disk, means for connecting the driving means to the drums for driving 30 same in a reverse direction.

6. A current motor comprising a flume, a power shaft, two pairs of drums on the power shaft, a clutch for each drum for connecting and disconnecting the same with 35 the power shaft, a plane for each pair of drums arranged in the flume, a cable for each of said drums having the ends connected with the respective planes and part looped around the respective drums, guiding 40 means for said cables whereby the ends of the cables approach the planes in opposite directions so that the planes moving in one direction will pull the cables and will be pulled by the cables when moving in the 45 opposite direction, and means carried by the planes for operating said clutches at the end of the power strokes.

7. A current motor of the character described comprising a flume, a power shaft, 50 two pairs of drums arranged on said shaft, a clutch for each drum for connecting the same with said shaft, a cable connected with each of said drums, a power plane for each of said pairs of drums arranged in said flume 55 connected with said cables for operating the same, each of said power planes having a sliding frame fitting the flume and a blade structure formed with a plurality of sections, means for normally locking the 60 respective blade structures in line with the respective frames, means for successively releasing said sections as the planes reach the end of their respective power strokes, means for moving said sections to a horizontal

position ready to move under the action of 65 gravity downwardly pivotally to an operative position, a supporting arm for preventing the downward movement of said sections until the respective frames are moved back to their starting points, means 70 for releasing said arm, and means for shifting said clutches at the end of each power stroke of said planes.

8. A current motor comprising a flume, a power shaft, a pair of planes formed to 75 fit the flume, a pair of drums on said power shaft for each of said planes, a cable for each of said drums, said cables being connected to the respective planes so that one plane will move on the power stroke while 80 the opposite plane will move on the return stroke, each of said planes having a pivotally mounted power blade, a catch or locking device for each of said power blades, means for automatically releasing said locking 85 catch at the end of the power stroke for each blade whereby said blades will be moved by the water to substantially a horizontal position, means for connecting and disconnecting said drums with said power 90 shaft, means for causing the drums of each plane when it finishes the power stroke to be reversed for pulling the plane back to the point at the beginning of the stroke, and means for moving said blades from the horizontal 95 position on the down stream side of the respective plane to a horizontal position on the upstream side at the completion of each return stroke whereby the blades will again assume a position across the flume 100 for causing the planes to act as power members.

9. A current motor of the character described comprising a flume, a pair of planes arranged in said flume and formed to fit 105 the flume so as to slide back and forth therein, a pivotally mounted power blade arranged in each plane, a catch for normally holding said power blade in an operative position, a stop arranged on the flume 110 for releasing said catch so that the power blades will be moved upwardly pivotally substantially to a horizontal position by the water at the end of the power stroke of each blade, a pivotally mounted arm arranged on each plane, a push lever having a hook end extending from the end of the respective arms at right angles thereto when the arms are in a horizontal position, means for moving said arms and push lever so as 115 to push the blade substantially horizontally from the down stream side of the planes to the upstream side of the planes immediately previous to the beginning of a new power stroke, a power shaft, and means for connecting said planes to said power shaft so that on the power stroke the power shaft 120 will be rotated by the power from the

planes, and on the return stroke the planes will be moved by power taken from the power shaft.

10. A current motor comprising a flume, 5 a pair of power planes arranged in said flume, a pair of cables connected with each of said planes, a power shaft, a drum loosely mounted on said power shaft connected with each of said cables so as to move the cables 10 or be moved thereby, a clutch plate arranged between each pair of drums, a clutch mem-

ber carried by each of said drums, means for shifting one of said clutches at the end of the power stroke of each plane, and means driven by said power shaft for rotating the 15 drums disconnected from said clutch plates whereby one of the planes will act as a driving member for the power shaft and the power shaft will drive the idle drums for pulling the other plane back to the beginning of its power stroke.

JOHN FRANKLIN LAYCOOK.
